[57] CLAIM

The ornamental design for a retractable aircraft mounted dry material spreader, as shown and described.

DESCRIPTION

FIG. 1 is a side elevation view of a retractable aircraft mounted dry material spreader, showing my new design, the opposite side being a mirror image thereof, the hinged material conduit, rotary spreader head, and skid being shown in retracted position for take-off and landing;

FIG. 2 is a view similar to FIG. 1 but with the hinged material conduit, rotary spreader head, and skid being shown in lowered, operative position;

FIG. 3 is a top plan view;

FIG. 4 is a bottom plan view;

FIG. 5 is a rear elevation view; and,

FIG. 6 is a front elevation view.

The broken lines in FIGS. 1 and 2 represent the fuselage of the aircraft, form no part of the design, and are for illustrative purposes only.
